UNITED STATES PATENT OFFICE.

HENRY E. BANDLOW, OF CHICAGO, ILLINOIS.

DESIGN FOR AN ELECTRIC TOASTER AND HEATER.

44,049.

Specification for Design.

Patented May 20, 1913.

Application filed May 8, 1912. Serial No. 695,995. Term of patent 7 years.

To all whom it may concern:

Be it known that I, HENRY E. BANDLOW, a citizen of the United States, residing in Chicago, in the county of Cook and the State of Illinois, have invented a new, original, and ornamental Design for an Electric Toaster and Heater, of which the following is a specification, reference being had to the accompanying drawings, forming a part thereof.

In the drawings: Figure 1 is a side eleva-

tion and Fig. 2 is a plan view of an electric toaster and heater embodying my novel design.

I claim:—

The ornamental design for an electric toaster and heater, as shown.

HENRY E. BANDLOW.
